UNITED STATES PATENT OFFICE.

FREDERICK KOHNLE, OF DAYTON, OHIO, ASSIGNEE, BY MESNE ASSIGNMENTS, TO THE MONARCH TAG COMPANY, A CORPORATION OF OHIO.

PRICE-TAG.

1,130,614.

Specification of Letters Patent. Patented Mar. 2, 1915.

Application filed March 11, 1912. Serial No. 688,160.

To all whom it may concern:

Be it known that I, FREDERICK KOHNLE, a citizen of the United States, residing at Dayton, in the county of Montgomery and State of Ohio, have invented certain new and useful Improvements in Price-Tags, of which the following is a specification.

My invention relates to a new article of manufacture comprising a continuous series of stapled price tags for merchandise, particularly of a fabric nature.

The object of the invention is to produce as an article of commerce these gang stapled tags, adapted to be easily made and delivered to users possessed of a new type of operating machine for severing the units of the gang and stapling them to the goods, which type of machine constitutes the subject matter of an independent invention, application for patent thereon being filed simultaneously herewith. In machines of this general character heretofore in use, the tags have been formed by the machine from a continuous strip of paper, the machine functioning not only to sever the strips into tag lengths, but to print the tags and to form and drive the staples both through the goods to be marked and the tags so formed by the machine. The new machine is much cheaper and simpler in character and is not burdened with the function of forming the staples and inserting them into the tags, and this invention is concerned with the production of an article having the capacity of responding to these new conditions of usage.

The features of the invention are more fully set forth in the description of the accompanying drawings, forming a part of this application, in which:

Figure 1 is a plan view showing the article. Fig. 2 is a side elevation. Fig. 3 is a plan view showing one tag severed.

1 represents the paper tape or continuous strip having marginal divisional notches 2 at regular intervals extending inwardly from one edge of the strip and terminating approximately at the medial line of the strip, the ends of these notches being in alinement.

3 represents the wire staples, one of which is clenched into the strip between each pair of division notches 2, defining the tag width. The prongs of the staples project upright from one side of the strip, the prongs of a

given staple being alined with one another and with the prongs of the other staple. It is to be understood that these strips are sold in convenient gang length, say each strip comprising twelve tags, and that when these strips are fed to the machine, the staple prongs are in an upright position when passing under the cutter, and the cutter merely operates to continue the cut from the terminal ends of the divisions 2 across the web of the strip, thus severing one of the units, shown in Fig. 3. The divisional notches 2 are also functional in providing on the strip engaging shoulders or abutments for the feeding mechanism of the machine, enabling the strip to be fed in the appropriate step movements. As these pre-stapled tag lengths are utilized as a new article of manufacture, the staples are placed upon the tags, so as to be securely held alined with the edge of the strip and with the free ends or prongs projecting at right angles to the plane of the strip, maintaining the same in a position to be acted upon by the clenching mechanism when fed into a machine, and also retain the staples upon the strip to prevent accidental displacement.

In the drawings, the preferred form of staple is illustrated bent in a peculiar outline, and which, as illustrated, comprises the bow portion 4 in a plane parallel with the plane of the strip projecting through the strip in the form of oppositely disposed U-bends 5 forming offsets or shoulders, thereby overlapping and engaging upon both sides of the strip with the terminals of the U-bends projecting toward the medial portion of the bow, and with the ends of the wire bent at right angles to the bow portion, to provide prongs 6. Thus, the staples are rigidly clenched to the strip in their spaced intervals between the divisional cuts and the prongs extend in an upright position at right angles to the plane of the strip, which is quite essential in feeding the same automatically within a machine, and thereby prevent the prongs from engaging the obstruction.

Having described my invention, I claim:

1. A new article of manufacture comprising a strip divided into tag lengths by divisional notches laterally extended from one edge of the strip inwardly toward the longitudinal medial line of the strip and in rela-

tively equal spaced parallelism, a staple permanently clenched through each tag length between the notches and serially in longitudinal alinement with the notched margin 5 of the strip with the notches extending beyond the longitudinal line of the staple to provide abutments, whereby the strip may be engaged to be fed in appropriate step intervals.

10 2. A new article of manufacture comprising a strip divided into tag lengths by divisional notches in parallelism extended from one edge of the strip toward its medial line, a series of staples secured to the strip 15 in relative longitudinal alinement and in parallelism with the notched marginal edge of the strip, one staple connected to each tag length between the divisional notches having its prongs passed through the tag and 20 offset or shouldered to overlap on the reverse side of the tag and the said notches

extending beyond the longitudinal line of staples providing abutments whereby the strip may be engaged to be fed in appropriate step movements.

25 3. A new article of manufacture comprising a strip divided into tag lengths by divisional apertures in longitudinal alinement at one of its margins, a staple secured to each tag length between the apertures in 30 longitudinal alinement, said apertures each providing a shoulder for engagement by feeding mechanism to internally advance the strip and a presevered portion adjacent the staple.

35 In testimony whereof, I have hereunto set my hand.

FREDERICK KOHNLE.
